UNITED STATES PATENT OFFICE.

HERMANN STRAUSSBERG, OF KANSAS CITY, MISSOURI.

DESIGN FOR A SPOOL-THREAD HOLDER.

SPECIFICATION forming part of Design No. 30,654, dated May 2, 1899.

Application filed April 10, 1899. Serial No. 712,556. Term of patent 7 years.

To all whom it may concern:

Be it known that I, HERMANN STRAUSSBERG, a citizen of the United States, residing at Kansas City, in the county of Jackson and State 5 of Missouri, have invented a new and original Design for Spool-Thread Holders, of which the following is a specification.

My invention relates to a new and useful design for spool-thread holders.

In the accompanying drawings, Figure 1 is a perspective view, Fig. 2 is a horizontal section, and Fig. 3 is a vertical longitudinal section, of a spool-thread holder, showing my new design; and the leading or material feature 15 of the same resides in the rectangular frame consisting of the parallel side pieces 1 2 and the parallel end pieces 3 4, connecting the ends of the side pieces, the rectangular bottom piece 5, projecting at one end beyond the 20 end piece 3, the rectangular top piece 6, of the same size and configuration as the bottom piece 5 and, like said bottom piece, projecting at one end beyond the end piece 3, the vertical columns 7 between the extensions of the 25 said bottom pieces, the arms 8, projecting outward from the end of the top piece 6, provided with hole-like figures 9 at their ends and the hole-like figures 10 and near the upper margins of the side piece 2.

Minor features of my design reside in the 30 cross-piece 11, the parallel and relatively long and narrow figures 12, intersecting and extending at right angles to the cross-piece 11, the cavities 13 in the end pieces 3 4, into which the ends of said long and narrow figures 12 project, the hinge-like figures 14, interposed between the bottom piece 5 and the end piece 4, the hinge-like figures 15, occurring at the junction of the side piece 2 with the top piece 6, the rectangular figures 16 upon said side piece 2 and below hole-like figures 10 of said side piece, the hinge-like figure 17 upon the top piece 6, adjacent to the end piece 4, the staple-like figure 18, projecting from said end piece 4, the hasp-like figure 19, extending from the hinge-like figure 17 to and beyond the staple-like figure 18, and the padlock-like figure 20, adjacent to and depending from the staple-like figure 18.

What I claim is—

The design for a spool-thread holder, substantially as herein shown and described.

In testimony whereof I affix my signature in the presence of two witnesses.

HERMANN STRAUSSBERG.
